CLAIM

The ornamental design for a dust box for a cleaning robot, as shown and described.

DESCRIPTION

1.1 is a front view of a dust box for cleaning robot showing a first embodiment of our new design;

1.2 is a back view thereof;

1.3 is a left view thereof;

1.4 is a right view thereof;

1.5 is a top view thereof;

1.6 is a bottom view thereof;

1.7 is a back, right perspective view thereof;

1.8 is a front, right perspective view thereof;

1.9 is a back, left perspective view thereof;

2.1 is a front view of a dust box for cleaning robot showing a second embodiment;

2.2 is a back view thereof;

2.3 is a left view thereof;

2.4 is a right view thereof;

2.5 is a top view thereof;

2.6 is a bottom view thereof;

(Continued)

2.7 is a back, right perspective view thereof;
2.8 is a front, right perspective view thereof; and
2.9 is a back, left perspective view thereof.
